UNITED STATES PATENT OFFICE.

MARY T. BUNNELL, OF NEW YORK, N. Y., EXECUTRIX OF JESSE H.
BUNNELL, DECEASED.

ELECTRIC SWITCHBOARD.

SPECIFICATION forming part of Letters Patent No. 644,844, dated March 6, 1900.

Application filed November 18, 1899. Serial No. 737,402. (No model.)

To all whom it may concern:

Be it known that JESSE H. BUNNELL, deceased, late a citizen of the United States, residing at New York, borough of Brooklyn, 5 county of Kings, and State of New York, did invent certain new and useful Improvements in Electric Switchboards, of which the following is a specification.

This invention is directed particularly to
10 an improvement upon electric switchboards
like that disclosed in United States Patent
No. 229,672, granted to Chas. E. Chinnock on
the 6th day of July, 1880; and it has for its ob-
ject to provide a switchboard of the type re-
15 ferred to in which more perfect circuit con-
nections may be effected between the indi-
vidual cross-bars of the board through the
agency of metallic switch-plugs like those
disclosed in the aforesaid patent, and the im-
20 provement will be fully understood by re-
ferring to the accompanying drawings, in
which—

Figure 1 is a plan view of an entire switchboard, and Fig. 2 is a similar plan view of the reverse side of the board. Fig. 3 is a transverse sectional view taken through Fig. 1 on the line $x-x$ and as seen looking thereat from the bottom toward the top of the drawings in the direction of the arrows; and Fig. 4 is a similar sectional view of a modified form of the invention, making it applicable for use in connection with very large central-station switchboards.

The switchboard disclosed in the patent granted to Chas. E. Chinnock, above referred to, embraces a series of metallic cross plates or bars secured to an insulating-base, one set of said bars being provided with switch-plug holes and the other set thereof with laterally-located flexible metallic strips, secured thereto by bolts and in the path of the entering ends of the switch-plugs. With such a switchboard there is a possibility of imperfect circuit connections between the flexible metallic strips and the cross-bars to which they are secured; nor is it always possible to make good circuit connections between the cross-bars should the attendant fail to insert the switch-plugs to their full depth. The present improvement overcomes these defects by making the circuit connections directly between any pair of

cross switch-bars by the metallic switch-plug itself and giving to the plug a firm mechanical and electrical connection between said plates by the agency of a strong spring located 55 on one side of the entering end of the plug in such manner as to cause it to act upon the principle of a lever, with at least two of its points of support bearing firmly and laterally against the two interconnected switch-bars. 60

Referring now to the drawings in detail for a full and clear understanding of the invention, such as will enable others skilled in the art to use the same, B B B' B' represent the four sides of the usual insulating-base of the 65 board, preferably of slate and held together by bolts g g, g g, F F F being insulating-feet on the under side of the board for securing it to a wall or partition.

1 2 3 4 5 6 7 represent one set of metallic 70
switch-bars having their ends secured by bolts
to the sides B' B', and 8, 9, 10, 11, 12, 13, and
14 the other set of metallic switch-bars hav-
ing their ends secured to the sides B B by
bolts g' g', &c., said switch-bars being pro- 75
vided with the usual plug-holes in alinement
with each other for the insertion of the switch-
plugs P' P² P³ P⁴ P⁵ P⁶ P⁷, the heads of said
plugs being insulated, as usual, and the body
parts p thereof made of metal and adapted to 80
fit snugly when in position within the holes
of the switch-bars, as clearly shown in Fig. 3.

b' , b^2 , b^3 to b^7 , inclusive, represent binding-posts secured to the ends of one set of the switch-bars, and b^8 , b^9 to b^{14} , inclusive, represent similar binding-posts secured to the ends of the other set of switch-bars. To the under surface of the lower set of switch-bars 8 9 10 11, &c., is secured by screws s a series of strong double springs S , so located that their 90 upwardly-curved yielding ends lie directly in the path of the switch-plugs before insertion and in such manner that when inserted they will cause said switch-plugs to be firmly held against the two switch-bars, which they connect by lateral pressure, thus insuring always an absolutely-perfect electrical connection between any pair of bars where a switch-plug may be inserted. By thus arranging the switch-bars so that the electrical connection 100 is direct from one bar to another through the interconnecting conducting switch-plug p

and by causing said plug to assume the function of a lever which is so fulcrumed as to bear frictionally and laterally against the two interconnected switch-bars an absolutely-sure 5 electrical connection is always effected, and by utilizing the springs S solely from a mechanical point of view the defect which is attributable to the springs in the before-mentioned Chinnoch patent is avoided.

10 In Fig. 4 of the drawings is illustrated in sectional view a modified form of the invention applicable to switchboards such as are used in large telephone and telegraph stations, where the lower cross-bars 8 to 14, inclusive, of Fig. 1 are done away with and a series of short individual metallic bars 10' 10² 10³ are substituted therefor and all secured to a slate or other insulating-board B² by screws extending downwardly through them 15 and through the springs S into metallic sleeves t, the lower ends of which constitute shoulders for metallic binding-screws d, to which the individual conductors (not shown) are secured. In other words, with this form of the 20 invention each individual conductor will be secured to its particular metallic sleeve t by the binding-screw d, and the metallic cross-bars 1 to 7, inclusive, will be provided with their usual binding-posts b', b² to b⁷, inclusive, as shown in Fig. 1. The circuit connection between any cross-bar 1 to 7, inclusive, and its corresponding short cross-bar 10' 10² 10³ is effected by the switch-plug p in the same manner as the circuit connection was 25 effected between the two sets of cross-bars illustrated in Fig. 1.

The present improvement is not limited to the especial details of construction herein shown and described for effecting a good electrical connection between the metallic cross-bars of a switchboard, as it is believed that the invention is broad enough to include a switchboard having metallic cross-bars or metallic switch-bars in which the circuit connection is effected directly by the action of a switch-plug held laterally against the switch-bars which it is designed to unite by any medium which causes the switch-plug to act upon the principle of a lever, so as to assure 40 actual conducting contact between the plug and the bars when it (the plug) is once inserted, and the claims hereinafter made are directed generically to the broad application of this principle.

55 Having thus described the invention, what is claimed, and what it is desired to secure by Letters Patent of the United States, is—

1. A switchboard having conducting switch-bars and one or more conducting switch-plugs

adapted to make electrical contact directly 6 between the bars; in combination with springs adapted to exert lateral pressure against the plugs in such manner as to cause them to bear frictionally and laterally against both of the interconnected bars.

2. A switchboard having conducting switch-bars and one or more conducting switch-plugs adapted to make electrical contact directly 7 between the bars; in combination with springs secured to one set of said bars and adapted to exert lateral pressure against the plugs in such manner as to cause them to bear frictionally and laterally against both of the interconnected bars.

3. A switchboard having conducting switch-bars provided with plug-holes in alinement with each other; in combination with switch-plugs and springs secured to one set of the switch-bars in such manner as to exert lateral pressure against the switch-plugs, when in 8 position, and cause them to bear frictionally and laterally against both of the interconnected bars.

4. A switchboard having conducting switch-bars provided with plug-holes in alinement 8 with each other; in combination with switch-plugs and double springs S secured to the under surface of the lower set of switch-bars and with their upturned ends in alinement with the plug-holes and adapted, when the 9 plugs are in position, to cause the same to bear frictionally against the interconnected bars.

5. A switchboard consisting of two sets of metallic cross-bars 1 to 7 inclusive and 8 to 9 14 inclusive, having their opposite ends secured to an insulating base or frame and provided with plug-holes in alinement with each other; in combination with switch-plugs P' P², &c., having conducting parts p, together with double springs S secured to the under surface of the lower set of switch-bars with their upturned ends in alinement with the plug-holes, the arrangement being such that when the switch-plugs are in position the springs 1 cause them to act upon the principle of a lever and exert strong frictional bearing against the interconnected bars, substantially as described.

In testimony whereof I have hereunto subscribed my name this 28th day of October, 1899.

MARY T. BUNNELL,
Executrix of the estate of Jesse H. Bunnell, deceased.
